STOP MOTION FOR LOOMS

John Jacob Kaufmann, Elkins Park, Pa., assignor to Steel Heddle Manufacturing Company, Philadelphia, Pa., a corporation of Pennsylvania

Application February 27, 1932, Serial No. 595,445

14 Claims. (Cl. 139—337)

My invention relates to stop motions for looms, and it relates more particularly to that type of stop motion in which an electrical circuit is employed in effecting the actuation of the 5 "knock-off" mechanism which brings the loom to a stop.

Heretofore, various arrangements have been suggested for completing an electrical circuit whenever a warp end breaks or becomes unduly 10 slack. These devices have been of various types, but the present invention is more particularly concerned with that type of stop motion in which the shed forming heddles are used as part of the detector mechanism. In some of 15 such devices it is necessary, and in others advisable, to supply the current to the harness frame in which the heddles are mounted only when the harness frame is in its lowermost shedding position, the reasons for which are well 20 known to those familiar with such devices.

One of the principal objects of my present invention is to provide improved means for supplying current at the proper time to contact members carried by the harness frame to the 25 end that an electrical circuit will be completed and the loom automatically stopped thereby, in the event that a warp end is broken or unduly slack.

A further and equally important object of my 30 invention is to provide improved means for completing the electrical circuit in the event of disarrangement or dropping of one or both ends of the harness frame, as happens when the straps for actuating the same become stretched 35 or broken, so that the loom will be automatically stopped under such circumstances.

A further object of my invention is to provide 30 unitary devices, one of which may be mounted at each end of the group of harness frames for accomplishing the foregoing objects.

A further object of my invention is to provide 40 means for accomplishing the foregoing objects, which will be relatively simple, inexpensive, efficient, and durable, and which may be readily applied to existing looms.

The nature and characteristic features of my 45 invention will be more readily understood from the following description, taken in connection with the accompanying drawings forming part 50 hereof, in which:

Figure 1 is a front elevation of a portion of one end of a loom harness frame, having associated therewith contact making devices embodying the main features of my present invention;

Fig. 2 is a similar view, showing the arrangement at the other end of the frame;

Fig. 3 is an elevational view, taken as indicated by the line 3—3 of Fig. 1, the cooperating contact members carried by the several frames 60 being shown in section;

Fig. 4 is a sectional view taken on the line 4—4 of Fig. 1;

Fig. 5 is an enlarged sectional view, taken on the line 5—5 of Fig. 3;

Fig. 6 is a sectional view taken on the line 6—6 of Fig. 2; and

Fig. 7 is a diagrammatic view illustrating one arrangement of circuits, and the parts controlling and controlled thereby, in connection with 70 which the device of my present invention is adaptable for use.

It will, of course, be understood that the description and drawings herein contained are illustrative merely, and that various changes and 75 modifications may be made in the structure disclosed without departing from the spirit of my invention.

Referring to the drawings, the harness frame there shown is of a common and well known type, 80 comprising top and bottom rails 10, connected at their ends by metallic end struts 11. The heddle supporting rods 12 are mounted at their ends in slots in the end struts 11, and serve to support the heddles 13, which are mounted thereon. The 85 heddles 13 may be of any of the usual types of metallic heddles, customarily used for controlling the warp ends to form the successive sheds during the operation of the loom.

The heddles 13 are mounted in the usual manner on the supporting rods 12 by means of the slots 14 near the ends thereof.

Each of the heddles 13 is also provided with an additional slot 15, through which extends a composite contact bar 16, comprising a central metallic strip 17, the lower portion of which is partially surrounded by a sheet of insulating material 18, and a metallic envelope 19, U-shaped in cross-section.

The construction and arrangement of the contact bar 16 is such that when the harness frame is in its lowermost position, and current is supplied to the contact bar 16 in the manner to be hereinafter described, a circuit will be completed by the dropping of one of the heddles 13, in the 105 event that the warp end controlled thereby should break or become unduly slack.

The composite contact bar 16 is mounted in the harness frame by means of slots 20 provided in the end struts 11, through which the contact 110

bar extends. At the left hand end of the harness frame, the central metallic strip 17 of the contact bar extends beyond the end of the U-shaped envelope 19 (see Fig. 1), and at the right hand end 5 of the harness frame, the U-shaped envelope 19 extends beyond the end of the central metallic strip 17 (see Fig. 2).

Each of the harness frames carries a contact member at each upper corner thereof. Each of 10 said contact members comprises a horizontal arm 21 and a vertically extending portion 22, whereby said contact member is secured to the harness frame by means of screws 23 which are threaded in portions of the side struts 11.

15 Each of the portions 22 of the contact member also serves to secure a leaf spring 24, the free end of which engages the extending portion of the composite contact bar 16, serving not only to confine the contact bar within the frame, but 20 also to convey the current to the respective portions of the contact bar which are engaged thereby.

The contact member at the left hand end of each harness frame is insulated therefrom by 25 means of a sheet 25 of insulating material, interposed between the portion of the leaf spring 24 which is engaged by the portion 22 of the contact member, and the portion of the side strut 11 of the harness frame to which said contact member is secured. Insulating bushings 26 and washers 27 serve to insulate the screws 23 from the contact member at the end of the harness frame where the leaf spring 24 is insulated from the side strut 11 by means of the insulating 35 strip 25.

At the right hand end of the harness frame, the contact member, and the portion of the spring 24 which is confined thereby, are grounded, or electrically connected to the portion of the 40 side strut 11 to which they are attached, by reason of the omission at this end of the harness frame of the insulating strip 25, bushing 26, and washers 27, which are provided at the other end of the frame.

45 At each end of the group or set of harness frames, and so positioned as to be engaged, in the manner hereinafter described, by the contact arms 21 which are carried at the respective ends of the harness frames, there is provided a device 50 which serves not only to supply current to the contact arms 21 when the harness frames reach their normal lowermost positions, but also to establish an electrical circuit whenever either or both ends of one of said frames drops below its 55 normal lowermost position, by reason of one or more of the actuating straps (not shown) becoming broken or unduly stretched.

The device above mentioned comprises a metallic bar 30, having a plate portion 31 extending 60 upwardly from the outer side thereof. A block 32 of insulating material is secured to the plate portion 31, and in this block of insulating material a plurality of hollow metallic pins 33 are 65 mounted in a row in close proximity to each other. The pins 33 extend upwardly from the block 32 and are adapted to be engaged by the contact arms 21 carried at the ends of the harness frames when the frames descend to form the shed.

70 Each of the pins 33 is impelled to its uppermost position by means of a coil spring 34, the upper end of which is positioned in the hollow interior of the pin, and the lower end of which extends to the lowermost position of the insulating block 75 32. Each of the pins is limited in its upward

movement by a shoulder 35, provided at the lower end thereof.

The lower end of each of the springs 34 bears 80 against a metallic strip 36, which extends along the under side of the insulating block 32. The metallic strip 36 is insulated from the bar 30 by means of a strip 37 of insulating material which is interposed between said metallic strip 36 and said bar 30. One end of the metallic strip 36 extends beyond the end of the bar 30 and the insulating block 32, for the connection thereto, by means of a screw 38, of a wire for conveying the current to said strip 36, and thence through the springs 34 to the pins 33.

85 It may here be noted that the upper marginal edge of the plate portion 31 of the bar 30 is positioned above the top surface of the insulating block 32, but below the plane of the upper ends of the pins 33 when said pins are in their uppermost positions. The upper edge of the plate portion 90 31 is also so located that the same will not be engaged by the contact arms 21 carried by the heddle frames when the heddle frames are in their normal lowermost positions, but will be engaged thereby in the event of the end of a harness 95 frame falling below its normal lowermost position by reason of the breaking or undue stretching of an actuating strap (not shown).

The bar 30 of the above described contact making device is provided with a lug 39, by means 105 of which it is secured to the eye end 40 of a supporting bar 41. The lug 39 of the bar 30 is fastened to the bar 41 by means of a bolt 42, which extends through said members. The bar 41 is adjustably secured in the split end of a bracket 110 43, being adapted to be clamped in its proper adjusted position by means of a clamping screw 44 (see Fig. 1). The bracket 43 is fastened by means of a set screw 45 to a bar 46, which is secured in any preferred manner to any suitable 115 portion of the loom frame. By the foregoing arrangement, a wide range of adjustment is provided, whereby the contact devices above described may be readily mounted in any of the various existing types of looms.

120 At one side of the loom, the bar 30 is secured directly to the bar 41, thereby being grounded, or electrically connected to the frame of the loom, through the bar 41, bracket 43, and bar 46. At the other side of the loom, the bar 30 is insulated 125 from the bar 41 by means of an insulating sleeve 47, surrounding the bolt 42 and insulating washers 48 and 49, on each side of the lug 39 (see Fig. 2).

Referring now more particularly to Fig. 7 of 130 the drawings, there is there shown a typical arrangement of circuits, and the parts controlling and controlled thereby, in connection with which the device shown in Figs. 1 to 6 of the drawings is adaptable for use, although it will, of course, 135 be understood that various other arrangements of circuits may be employed if desired.

As there shown, 50 represents a source of electrical energy, such for example as a battery, the negative terminal of which is connected by wire 140 51 to a stationary contact member 52, mounted upon, but suitably insulated from, a portion of the loom frame, adjacent the "knock-off" lever 53. The "knock-off" lever 53 carries a spring arm 54, adapted, in the normal operation of the loom, 145 to engage the contact member 52. The "knock-off" lever 53 is grounded, or electrically connected to the main frame of the loom, this grounding being indicated by the wire 55 extending to the ground 56.

The positive terminal of the battery 50 is connected by wire 57 to one end of the coil 58 of an electro-magnet. The other end of the coil 58 of the electro-magnet is connected by wire 59 to the pins 33, which are adapted to be engaged by the contact arms 21 carried at the left hand end of the harness frames. The bar 30, at this side of the loom, is grounded, or electrically connected to the main frame of the loom, this grounding being indicated by the wire 60 and ground 61.

A shunt line 62 extends from wire 59 to the bar 30 at the right hand side of the loom. The pins 33 at this side of the loom are grounded, or electrically connected to the frame of the loom, this grounding being indicated by the wire 63 and ground 64.

Adjacent the pole 65 of the electro-magnet is a movable armature 66, carried by a pivoted lever 67, whereby said lever will be actuated when the current passes through the coil 58 of the electro-magnet. The free end of the lever 67 is connected by means of a rod 68 to a movable dog 69, carried by a shipper rod 70.

The dog 69 is adapted to be raised when the armature 66 is attracted to the pole piece 65 of the electro-magnet, to cause said dog 69 to be engaged by a lug 71, carried by the lay 72, and thereby to cause the shipper rod 70 to be actuated by the movement of the lay 72 whenever the electro-magnet is energized. The shipper rod 70 also carries a lug 73, which is adapted to engage and actuate the "knock-off" lever 53 when said shipper rod 70 is thus actuated.

A stationary contact member 74 is arranged adjacent the lever 67, and is adapted to be engaged thereby whenever the electro-magnet is energized. This contact member 74 is connected by wire 75 to wire 59. The lever 67 is grounded, or electrically connected to the frame of the loom, this grounding being indicated by wire 76 and ground 77.

The operation of the device may now be explained. It may first be pointed out that when the loom is functioning normally, the "knock-off" lever 53 will be in such position that the spring arm 54 carried thereby will be in contact with the member 52, whereby, if the circuit be otherwise established, the current may flow from the negative terminal of the battery 50, through wire 51, to contact member 52, thence by spring arm 54, and wire 55, to ground 56.

When, however, the "knock-off" lever 53 is in the position assumed when the loom is stopped, the spring 54 will be separated from the contact member 52, thereby maintaining the circuit open whenever the loom is not operating.

When the loom is functioning normally, the circuit will be open, but in the event of certain contingencies, a number of alternative paths for the current are provided, as will hereinafter appear. The operation with respect to the stopping of the loom whenever a warp end breaks or becomes unduly slack will be first described.

When a harness frame descends to its lowermost shedding position, the tension imparted to the warp ends controlled by the heddles in said frame will cause the entire set of heddles therein to be raised, this action being permitted by reason of the provision of the slots 14 in the heddles 13. The heddles 13 will then slightly raise the composite contact bar 16. Should, however, one of the warp ends be broken or unduly slack, the heddle for controlling the same will drop, thus completing an electrical circuit through the heddle across the central metallic

strip 17 and the outer metallic envelope 19 of the composite contact bar 16.

When the harness frame is in its normal lowermost position, the contact arm 21 at each end thereof will engage and slightly depress one or more of the pins 33. A circuit will then be established, the current passing from the negative terminal of the battery 50, by wire 57, through the coil 58 of the electro-magnet, thence by wire 59, to the pins 33 adjacent the left hand end of the harness frames, thence by arm 21 and vertical extension 22 of the contact member carried at the upper left hand corner of the harness frame, to the leaf spring 24 associated therewith.

The current will then pass from leaf spring 24 to the central metallic strip 17, thence through the dropped heddle, to the outer metallic envelope 19, thence by leaf spring 24 at the upper right hand corner of the harness frame, to the vertical extension 22 and arm 21 of the contact member carried at this place, thence passing by pins 33 at the right hand side of the group of harness frames, by wire 63, to ground 64.

When the current passes as aforesaid, the electro-magnet will be energized and the armature 66 of the lever 67 will be attracted toward the pole piece 65 of said electro-magnet. In this manner, the free end of the lever 67 will be raised, causing the dog 69 carried by the shipper rod 70 to be raised in the path of the lug 71 carried by the lay 72. As the lay moves to its rearward position, the lug 71, by reason of its engagement with the dog 69, will cause the shipper rod 70 to be actuated, and thereby, through the lug 73, the "knock-off" lever 53 will be actuated to bring the loom to a stop in the usual manner, at which time the circuit will be opened as hereinbefore described, by reason of the separation of the spring arm 54, carried by the "knock-off" lever 53, and the stationary contact member 52, to which the wire 51 extends.

When the circuit is first closed as aforesaid, this closing of the circuit is only momentary, that is to say, while the harness frame remains in its normal lowermost position, but it is desirable that the electro-magnet be maintained energized until the lug 71 carried by the lay 72 has had an opportunity to engage the dog 69 carried by the shipper rod 70, and for this purpose the contact member 74, which is adapted to be engaged by the lever 67, is provided.

When the lever 67 touches the contact member 74, the current will then flow from line 59, through wire 75, to the contact member 74, thence through said lever 67, by wire 76, to ground 77, thus maintaining the electro-magnet energized, and holding the dog 69 in its raised position, to insure the actuation of the shipper rod 70 and "knock-off" lever 53, notwithstanding the subsequent opening of the circuit through the contact bar 16 of the harness frame, when the contact arms 21 leave the pins 33 by reason of the upward movement of the harness frame.

In the event of the breaking or undue stretching of any of the straps for actuating the harness frames, one or both ends of the harness frame controlled thereby will be permitted to drop below its normal lowermost position, whereupon the contact arm 21 will cause the pins 33 engaged thereby to be further depressed, until the contact arm 21 engages the top marginal edge of the plate 31 extending upwardly from the bar 30.

When this occurs at the left hand end of the harness frame, the current will flow from line 59

150

- which extends from the coil 58 of the electro-magnet, to the pins 33, thence by arm 21, to plate 31, to bar 30, thence by wire 60 to ground 61, thus completing the circuit and energizing the electro-magnet in the same manner as hereinbefore described with respect to the operation when one of the heddles drops by reason of its warp end becoming broken or unduly slack.
- When the right hand end of a harness frame drops below its normal lowermost position, the current will flow from line 59 which extends from the coil 58 of the electro-magnet, through line 62, to the bar 30 and the plate 31 which extends upwardly therefrom, thence by contact arm 21 to the pins 33, thence by wire 63, to ground 64 thus completing the circuit and energizing the electro-magnet to cause the same to function as hereinbefore described.
- It will, of course, be understood that the device for supplying the current to the harness frame, and for completing the circuit whenever one or both ends of the harness frame drop below its normal lowermost position, may be used in connection with various other types of devices for making contact within the harness frame whenever a heddle drops by reason of a warp end becoming broken or unduly slack.
- I claim:
1. In a stop motion for looms, means for stopping the loom including an electrical circuit, means in the harness frame for closing said circuit when a warp end is broken or unduly slack, a contact arm carried by the harness frame and included in said circuit, and a member positioned whereby said contact arm will make contact therewith and also close the circuit when the frame falls below its normal lowermost position.
  2. In a stop motion for looms, means for stopping the loom including an electrical circuit; contact arms carried by the harness frames and projecting therefrom; and a member positioned whereby a contact arm will make contact therewith only when a frame falls below its normal lowermost position; the circuit being completed through said contact arm when it contacts with said member.
  3. In a stop motion for looms, electromagnetically controlled means for stopping the loom; a circuit for controlling said means; contact arms carried by the harness frames and projecting therefrom; and a member positioned whereby a contact arm will make contact therewith only when a frame falls below its normal lowermost position; the circuit being completed through said contact arm when it contacts with said member.
  4. In a stop motion for looms, means for stopping the loom including an electrical circuit; contact arms carried by the harness frames; and devices adapted to be engaged by the contact arms, each of said devices comprising members electrically insulated from each other, one of said members being positioned whereby a contact arm will make contact therewith only when a frame falls below its normal lowermost position, and the contact arm serving to close the circuit when it contacts with both of said members.
  5. In a stop motion for looms, electromagnetically controlled means for stopping the loom; a circuit for controlling said means; contact arms carried by the harness frames; and devices adapted to be engaged by the contact arms, each of said devices comprising members electrically insulated from each other, one of said members being positioned whereby a contact arm will make contact therewith only when a frame falls below its normal lowermost position, and the contact arm serving to close the circuit when it contacts with both of said members.
  6. In a stop motion for looms, means for stopping the loom including an electrical circuit, harness frames having means for completing said circuit when a warp end is broken or unduly slack; contact arms carried by the harness frames; and devices adapted to be engaged by the contact arms, each of said devices comprising members electrically insulated from each other; the contact arms being adapted to make contact with one of said members when the frame descends to form the shed; the other of said members being positioned whereby a contact arm will make contact therewith only when a frame falls below its normal lowermost position, and the contact arm serving to close the circuit when it contacts with both of said members.
  7. In a stop motion for looms, electromagnetically controlled means for stopping the loom; a circuit for controlling said means; harness frames having means for completing said circuit when a warp end is broken or unduly slack; contact arms carried by the harness frames; and devices adapted to be engaged by the contact arms, each of said devices comprising members electrically insulated from each other, the contact arms being adapted to make contact with one of said members when the frame descends to form the shed, the other of said members being positioned whereby a contact arm will make contact therewith only when a frame falls below its normal lowermost position, and the contact arm serving to close the circuit when it contacts with both of said members.
  8. In a stop motion for looms, means for stopping the loom including an electrical circuit, harness frames having means for completing said circuit when a warp end is broken or unduly slack; contact arms carried by the harness frames; and devices adapted to be engaged by the contact arms, each of said devices comprising depressible members and a fixed member electrically insulated from said depressible members; the contact arms being adapted to make contact with the depressible members when the frame descends to form the shed; the fixed member being positioned whereby a contact arm will make contact therewith only when a frame falls below its normal lowermost position, and the contact arm serving to close the circuit when it contacts with the fixed member.
  9. In a stop motion for looms, electromagnetically controlled means for stopping the loom; a circuit for controlling said means; harness frames having means for completing said circuit when a warp end is broken or unduly slack; contact arms carried by the harness frames; and devices adapted to be engaged by the contact arms, each of said devices comprising depressible members and a fixed member electrically insulated from said depressible members, the contact arms being adapted to make contact with the depressible members when the frame descends to form the shed; the fixed member being positioned whereby a contact arm will make contact therewith only when a frame falls below its normal lowermost position, and the contact arm serving to close the circuit when it contacts with the fixed member.
  10. In a stop motion for looms, means for stopping the loom including an electrical circuit, harness frames having means for completing said circuit when a warp end is broken or unduly slack.

- slack; contact arms carried at the ends of the harness frames; and devices arranged adjacent the ends of the harness frames and adapted to be engaged by the contact arms, each of said devices comprising compressible members and a fixed member electrically insulated from said compressible members; the contact arms being adapted to make contact with the compressible members when the frame descends to form the shed; the fixed member being positioned whereby a contact arm will make contact therewith only when a frame falls below its normal lowermost position, and the contact arm serving to close the circuit when it contacts with the fixed member. 80
11. In a stop motion for looms, electromagnetically controlled means for stopping the loom; a circuit for controlling said means; harness frames having means for completing said circuit when a warp end is broken or unduly slack; contact arms carried at the ends of the harness frames; and devices arranged adjacent the ends of the harness frames and adapted to be engaged by the contact arms, each of said devices comprising compressible members and a fixed member electrically insulated from said compressible members; the contact arms being adapted to make contact with the compressible members when the frame descends to form the shed; the fixed member being positioned whereby a contact arm will make contact therewith only when a frame falls below its normal lowermost position, and the contact arm serving to close the circuit when it contacts with the fixed member. 85
12. In an electrical warp stop motion for looms, harness frames having means for completing a circuit when a warp end is broken or unduly slack; contact arms carried by the harness frames; a device adapted to be engaged thereby, said device comprising a metallic bar, an insulating block secured thereto, and a plurality of compressible pins mounted in said insulating block; said pins being included in the circuit and positioned to be engaged by a contact arm when a harness frame descends to its normal lowermost position; the metallic bar having a portion positioned to be engaged by a contact arm only when a portion of the frame falls below its normal lowermost position, thereby to complete the circuit independently of the circuit completing means in the harness frame; and means controlled by the circuit for stopping the loom. 90
13. In an electrical warp stop motion for looms, harness frames having means for completing a circuit when a warp end is broken or unduly slack; contact arms carried by the harness frames; and a metallic bar having a portion positioned to be engaged by a contact arm only when a portion of the frame falls below its normal lowermost position, thereby to complete the circuit through said contact arm; and means controlled by the circuit for stopping the loom. 95
14. In an electrical warp stop motion for looms, harness frames having means for completing a circuit when a warp end is broken or unduly slack; contact arms carried by the harness frames; a device adapted to be engaged thereby, said device comprising a metallic bar, an insulating block secured thereto, and a plurality of compressible pins mounted in said insulating block; said pins being included in the circuit and positioned to be engaged by a contact arm when a harness frame descends to its normal lowermost position; the metallic bar having a portion positioned to be engaged by a contact arm only when a portion of the frame falls below its normal lowermost position, thereby to complete the circuit independently of the circuit completing means in the harness frame; and means controlled by the circuit for stopping the loom. 100
15. In an electrical warp stop motion for looms, harness frames having means for completing a circuit when a warp end is broken or unduly slack; contact arms carried by the harness frames; and a metallic bar having a portion positioned to be engaged by a contact arm only when a portion of the frame falls below its normal lowermost position, thereby to complete the circuit independently of the circuit completing means in the harness frame; and means controlled by the circuit for stopping the loom. 105
16. In an electrical warp stop motion for looms, harness frames having means for completing a circuit when a warp end is broken or unduly slack; contact arms carried by the harness frames; and a metallic bar having a portion positioned to be engaged by a contact arm only when a portion of the frame falls below its normal lowermost position, thereby to complete the circuit independently of the circuit completing means in the harness frame; and means controlled by the circuit for stopping the loom. 110
